SEMAUTOMATIC ELECTRIC NAILER

Arthur J. Curtis, Walla Walla, Wash., assignor
of one-half to David G. Robanske, Walla Walla,
Wash.

Application January 26, 1949, Serial No. 72,845

2 Claims. (Cl. 1—46)

1

The present invention relates to a semi-automatic electric hammer and nail set, and more particularly to a portable electrically operated hammer in which the nails or other fastening elements are fed to the pathway of the hammer nail set.

The primary object of the invention is to provide a semi-automatic electric hammer having a magazine feed which is controlled by a single actuator manually operated to close a circuit through alternate solenoids for controlling the hammer movement.

Another object is to provide a semi-automatic electric hammer and nail setting device in which the nails or other fastening elements are fed to the pathway of the hammer by means of a magazine fed manually actuated control cylinder to permit the nails or other fastening elements to be moved into the pathway of the hammer or nail set individually.

Another object is to provide a semi-automatic electric hammer and nail setting device which is capable of being operated manually with one hand, thus leaving the other hand free to hold various workpieces in place during nailing.

Another object is to provide a semi-automatic electric hammer and nail setting device which can be manually controlled to feed a nail or other fastening means in the pathway of the nail set and hammer and simultaneously operate the hammer to produce a single stroke or a series of repeated strokes without feeding another nail or fastening element.

Another object is to provide a semi-automatic electric hammer and nail set in which the hammer is magnetically controlled by a manual selectively control switch to enable an electro-magnet to be energized to deliver the power stroke by attracting the armature of the hammer, and to then be retracted by manipulation of the selective control switch which energizes another solenoid or electro-magnet to retract the hammer and nail set to its starting position.

Another object is to provide a semi-automatic electric hammer and fastener feeding device having a hand grip which is provided with a control switch which is operated by the user when grasping the pistol grip to complete the circuit through the control solenoid and render the trigger operator switch or selective control operable.

Another object is to provide a semi-automatic electric hammer in which the fastening elements are contained in a magazine and fed to a control cylinder into the path of the hammer or nail set by a step to step motion controlled by the

selective trigger switch, thus enabling a nail or fastening element to be projected into the path of the nail set or hammer by manipulating the trigger control switch through a full stroke movement.

Another object is to provide a semi-automatic electric hammer having a trigger operated control switch capable of being selectively operated to cause repeated power strokes to be imparted to the nail set without feeding another fastening element, and to be selectively manipulated to feed a nail or other fastening element into the path of the nail set or hammer upon each stroke or power movement of the hammer.

15 Other objects and advantages of the invention will become apparent during the course of the following description of the accompanying drawings, wherein:

Figure 1 is a longitudinal cross sectional view 20 of the semi-automatic electric hammer and nail set showing the arrangement of the electrically operated hammer control solenoids, the manner in which the nails or other fastening elements are individually fed to the pathway of the hammer and the manual control mechanism for the solenoids of the electric hammer motor and the individual feed mechanism, the armature and hammer being shown in their retracted position.

Figure 2 is a longitudinal cross sectional view 30 of the semi-automatic electric hammer and nail set similar to Figure 1, but showing the solenoid armature and nail set at the end of its power stroke with the nail or other fastening element driven home in the workpiece.

Figure 3 is a vertical cross sectional view taken 35 on line 3—3 of Figure 1 and looking in the direction of the arrows, to illustrate the control cylinder feed and magazine for supplying fastening elements to the control cylinder.

Figure 4 is a vertical cross sectional view taken 40 on line 4—4 of Figure 1 and looking in the direction of the arrows, to illustrate the control linkage for the nail feed and the arrangement of the solenoid armature.

Figure 5 is a rear elevational view showing the hand grip switch for maintaining the circuit closed from the power source during operation of the electric hammer and nail set.

Figure 6 is a fragmentary vertical cross sectional view similar to Figure 3, but greatly enlarged to illustrate various structural details of the fastening element feed cylinder and the arcuate slot in the hammer barrel.

Figure 7 is a vertical fragmentary cross sectional view taken on the irregular line 7—7 and

looking in the direction of the arrows to illustrate the fastener element feeding cylinder and the circumferentially spaced projections engageable by the control linkage to advance the cylinder a predetermined angular distance and thus project a nail into the hammer pathway.

Figure 8 is a fragmentary view of the trigger control switch showing the same greatly enlarged to illustrate the spring loaded contact for permitting repeated operation of the hammer without feeding a fastening element to the hammer pathway.

Figure 9 is a transverse cross sectional view taken on the oblique irregular line 9—9 of Figure 1 and looking in the direction of the arrows, to illustrate the hand grip switch and the variable resistance control in circuit with the selector trigger operated switch.

Figure 10 is a fragmentary cross sectional view taken on the oblique line 10—10 of Figure 1 and looking in the direction of the arrows to show the selector switch and the slide guide controlled by the movement of the hand grip trigger.

Figure 11 is a horizontal cross sectional view taken on line 11—11 of Figure 1 and looking in the direction of the arrows, to illustrate the shape of the magazine and the manner in which the fastening elements are arranged therein.

Figure 12 is a horizontal cross sectional view similar to Figure 11, but showing a slightly different fastening element or nail, and

Figure 12A is a horizontal cross sectional view likewise similar to Figure 11 and showing another type of nail in the magazine.

In the drawings, and more in detail, there is shown a semi-automatic hammer and nail set including a housing generally designated 5 in which there is mounted reciprocating motor means generally designated 6 for controlling the movement of the hammer into the path of which nails or other fastening elements are fed from a magazine generally designated 7. The housing 5 is provided with a pistol hand grip 8 likewise generally designated.

The housing 5 is of cylindrical section and is divided diametrically to provide complementary housing sections 10 which are formed of plastic or other insulating material for safety purposes. The hand grip 8 is formed by complementary projections 11 integrated with the sections 10 so that when the sections are fastened together by fastening elements such as bolts or the like 12, the hand grip sections 11 will mate and can be bolted together by similar fastening elements 13. The cylindrical housing formed by the semi-cylindrical sections 10 is closed at the rear end by sector-shaped walls 14 formed integral with the respective casing sections. Each of the housing sections 10 is provided with a tapered front wall portion 15 having a circular cut-away portion 16 to form an opening in the front end of the housing when said sections are placed together.

Further, each of the housing sections 10 are chambered as at 17 and 18 to provide enlarged bores separated by an annular wall 19 extending inwardly a short distance and terminating in a round inner wall 20, thus providing a bore between the housing sections of a size and shape to receive and support a pair of motor casings 21 and 22 that are formed of insulating material and which are threadedly connected as at 23. The motor section 21 is provided with a tapered end wall portion 24 which engages the tapered wall 15 of the housing and projects through the open-

ing 16 to form a barrel 25 of reduced diameter having a central bore 26.

Electromagnet or solenoid coils 27 and 28 are mounted on the cylindrical casing sections 21 and 22, with one end of the coil 27 abutting a shoulder 29 on the tapered portion 24, while the other end abuts the annular wall 19 of each casing section. Similarly, the motor coil or magnet 28 has one end abutting an annular shoulder 30 on the casing section 22, while the opposite end is held in place by means of a nut 31 on the correspondingly threaded end 32 of the casing section 22.

Reciprocably mounted within the motor casing sections 21 and 22 is an armature 33 which is adapted to be alternately attracted by the coils 27 and 28 in a manner which will be presently described. The forward end of the armature 33 is provided with a longitudinal bore 34 for receiving the rear end of a combined nail set and hammer 35 which is held in place by set screws 36. The free end of the hammer or nail set is mounted to move to and fro within the bore 26 of the barrel 25 and drive nails or other fastening elements projected into the path of said hammer and nail set. The front end of the armature is tapered as at 37 to conform to the tapered wall 24 of the reciprocating motor casing section 21 and thus form a limiting stop for said armature.

In order to feed nails or other fastening elements to the hammer pathway or bore 26 the magazine 7 is arranged on the front of the housing 5, and includes a channelway having side walls 38 connected at one end by a wall 39 having offset portions 40 to provide an enlarged end chamber to accommodate the head of the nail. The opposite end is closed by a wall 41 affixed to the forward edges of the walls 38 and the walls 40 are reinforced by triangular shaped ribs 4. A closure 42 is hinged to the rear wall 39 as at 43 and a clasp 44 is affixed to the swinging end of the closure and engages a projection 45 on the front wall 41. The upper portion of the magazine 7 is shaped to provide a feed cylinder housing and as shown in Figure 9, the side walls 38 are curved as at 46 to form a housing of circular shape. The front wall of the upper portion of the wall 41 is rounded as at 47 to close the front portion of the cylinder housing and similarly, the rear wall 39 of the magazine is enlarged adjacent its upper end to provide a rear disc-like wall 48 for the cylinder housing. The curved walls 46 are provided with extensions 49 which are affixed to the barrel 25 by screws or the like 50. The rear wall 39 of the magazine 7 has welded or otherwise affixed thereto a threaded member or nut 52 for receiving a screw 3 extending through a projection on the lower portion of a depending casing extension 53. The casing extension 53 is formed by complementary housing portions each of which is integral with one of the housing sections 10 as shown in Figure 4.

Mounted in the cylinder housing 46 is a feed cylinder comprising a pair of disc-like members 55 connected by a sleeve 56, and each of said disc-like members is provided with a series of peripheral indentations 57 to form nail receiving pockets. The feed cylinder is supported upon a pin or screw 58 which is threaded in the rear wall 48 of the cylinder housing as shown in Figure 9, and extends through an opening in the front wall 41. The barrel 25 is provided with a pair of arcuate slots 59 to permit the cylinder ends 75 to pass at a point below the bore 26 or pathway

of the hammer and in addition, the barrel 25 is cut away as at 60 to provide an arcuate passage-way communicating the interior of the cylinder 46 with the hammer pathway or bore 26 and thus enable nails N to be projected into the pathway in advance of the hammer 35. The nails N are fed upwardly to the feed cylinder by means of a follower 61 yieldingly urged upwardly by means of a sinuous leaf spring 62.

One of the cylinder ends or discs 55 is provided with a series of projections 63, Fig. 7, which are adapted to be engaged by a bell crank lever 64 mounted on a pin 65 which has its ends received in opposed slots 66 one in each of the mating faces of the casing sections 10. The bell crank lever 64 is provided with an arm 67 which projects through a slot 68 in the rear wall 48 of the magazine so that its free end will be presented to the projections 63 as shown in Fig. 7. A spring 69 is provided for urging the bell crank lever 64 in a direction toward the feeding cylinder, but yet permitting the free end of the arm 67 to slide away from the projections during the retraction of the bell crank lever. A control trigger 70 is mounted on a pin 71 which has its ends received in openings formed in the extensions 53 of the housing sections 10, and said trigger operates in corresponding cutouts 73 in the mating faces of the pistol grip sections 11. An extension 72 is formed on the trigger 70 and is connected to the bell crank lever 64 by means of a link 74 held in place by pins 75 and 76 on the bell crank lever and extension respectively. A coil spring 77 has one end affixed to the link 74, and its opposite end anchored to the casing as at 78 to retract the link 74 and cause the arm 67 to be moved downwardly about its supporting pin 65 when the trigger is released.

The pistol grip handle 8 is provided with a bushing 79 through which extends an electric cable 80 which is adapted to be attached to a suitable source of electrical energy. One of the electrical conductors 81 of the cable is electrically connected to a switch contact 82 which is supported on a block 83 carried by one of the casing sections while the other electrical conductor 84 is connected to a slider 85 movably mounted in a slot 86 so that its contact member 87 will slidably engage an electric resistance element 88. The resistance element 88 is electrically connected by means of a conductor 89 to a switch arm 90^a, which is fixed to a support 91 formed integral with one of the pistol grip sections 11 of the pistol grip 8. A pair of contacts 92 and 93 are carried by the switch arm 90^a and are adapted to be alternately engaged by movable contacts 90 and 94 carried by a slide 95 operable in a slide guide 96 supported or formed integral with the casing sections 11 as shown in Figure 10. The slide 95 is provided with an extension 98 which is connected to the trigger 70 by means of a link 99 by suitable pivot pins 100 and 101. The other end of the slide 95 is provided with an arm 102 in which is mounted a reciprocating pin 103 having an enlarged head 104, which is adapted to engage a stop member 105 on the arm 102 and is yieldingly urged into engagement with the stop 105 by means of a coil spring 106 which has one of its ends abutting the arm 102, and its opposite end in engagement with a washer 107 on the inner end of the pin 103. The extreme inner end of the pin 103 is provided with a contact 94, which is adapted to engage the fixed contact 93 when the trigger 70 is moved outwardly by the spring 77. The contact 90 is electrically connected to one

end of the coil 27 by means of an electrical conductor 109, while the contact 94 is electrically connected to the coil 28 by means of a conductor 110. The opposite ends of the coils 27 and 28

- 5 are connected together by electrical conductors 111 and 112 which are connected at 113 and from the point 113 a conductor extends downwardly into the pistol grip 8, where it is attached to a contact 114 carried by a movable switch arm 115
- 10 which is pivoted as at 116 on a pivot pin having its ends mounted in suitable bearing openings in the opposed sections of the pistol grip. The movable arm 115 operates in a slot 117 in the pistol grip, and a spring 118 is affixed to one of the sections 11 on a projection 119 and has its free end in engagement with the operating arm 115 to normally hold the contacts 82 and 114 separated.
- 15 In Figures 12 and 12A the magazine 7a and 7b are identical in form to the magazine 7, but different forms of nails are shown as being held by the magazines. In Figure 12 the nail N' is shown as being provided with a countersunk head, while the nail shown in 12A as at N'' is formed with a relatively small head.

- 55

In operation, the magazine is filled with a plurality of nails N and the hand grip 8 is grasped which closes the circuit through the contacts 82 and 114 as shown in Figures 1 and 2. The barrel 25 is then presented to the work W, Figure 2, and the trigger 70 is depressed to simultaneously rotate the feed cylinder and project a nail into the bore 26 and close the circuit between the contacts 90 and 92. When the contacts 90 and 92 are closed the coil 27 is energized and causes the armature 33 to deliver a power blow through the hammer 35 to the nail projected into the bore 26. The outer part of the barrel 25 is provided with an inclined surface 25a which extends outwardly from the arcuate slot 59 that receives the outer disc of the feed cylinder and this inclined surface facilitates guiding the point of a nail or the like to the bore of the barrel. Upon release of the trigger 70 the trigger and slide 95 will travel forwardly under the influence of the spring 77 and the contacts 93 and 94 will engage and thus electrically connect the coil 28 to the source of electrical energy and energize said coil. When this occurs, the armature 33 will be retracted to the right hand end of the portable housing 10, and simultaneously the arm 67 of the bell crank lever 64 will move downwardly over the wedge-shaped projections 63 and will be positioned in back of one of the projections as shown in Figure 7 for again moving the feed cylinder upon manual manipulation of the trigger 70.

Should it be desired to cause the hammer 35 to deliver a repeated number of blows without feeding another nail to the bore 26, the trigger 70 is depressed to cause the initial feeding of a nail into the hammer pathway 26 which simultaneously closes the contacts 90 and 92, and causes the coil 27 to be energized as before to deliver a power blow to the nail. Instead of completely releasing the trigger 70, it may be moved forwardly by releasing the pressure thereon slightly as shown in Figure 2 so as to cause the contacts 93 and 94 to be engaged and thus energize the coil 28 and cause the armature 33 and hammer to be retracted. This movement is not sufficient to cause the arm 67 to move an appreciable distance to engage the next or adjacent projection 63 and hence, the trigger 70 may be oscillated by depressing and releasing the same a sufficient amount to cause the contacts 90—92 and 93—94 to be alternately engaged and disengaged. This

motion will cause the armature 33 to travel to and fro within the motor casing sections 21 and 22 and strike a series of power blows on the nail N in the work W.

The pivoted arm 115 as has been explained, completes the return circuit from both of the coils to the electrical conductor 81 when the pistol grip 8 is grasped for manipulation.

It is to be understood that the form of the invention herewith shown and described is to be taken as a preferred embodiment thereof, and that various changes in the shape, size and arrangement of parts may be resorted to without departing from the spirit of the invention or the scope of the subjoined claims.

I claim:

1. In an electric hammer, a portable housing having a hand grip, a barrel on said housing providing a hammer pathway, a hammer reciprocably mounted in said barrel, motor means 20 for reciprocating said hammer in said pathway, a feed cylinder for projecting fastening elements into said hammer pathway, link means for moving said cylinder a predetermined angular distance, and manually operable means on said 25 hand grip for simultaneously controlling the reciprocating movement of said motor means and operating said cylinder.
2. In an electric hammer, a housing having a pistol hand grip, a barrel at one end of said 30

housing providing a hammer pathway, a hammer and nail set reciprocably mounted in said barrel, motor means in said housing, an armature for said motor means connected to said 5 hammer, a cylinder mounted adjacent said barrel for projecting fastening elements into said pathway in advance of said hammer, step by step ratchet means for rotating said cylinder a predetermined angular distance, a trigger operated control switch in said hand grip for controlling said motor means, and linkage connecting said ratchet means to the trigger of said control switch whereby manual operation of said trigger will project a fastening element into said 10 pathway and operate said motor means.

ARTHUR J. CURTIS.
